W. J. BARNETT

ROCK DRILL

Filed Nov. 3, 1925

INVENTOR
WILLIAM J. BARNETT
BY *W. J. Barnett & Co. Inc.*
HIS ATTORNEY

UNITED STATES PATENT OFFICE.

WILLIAM JAMES BARNETT, OF KENILWORTH, TRANSVAAL, SOUTH AFRICA, ASSIGNOR
TO INGERSOLL-RAND COMPANY, OF JERSEY CITY, NEW JERSEY, A CORPORATION
OF NEW JERSEY.

ROCK DRILL.

Application filed November 3, 1925. Serial No. 66,491.

This invention relates to rock drills of the hammer type and like percussive tools.

In drills of the type referred to and like percussive tools it is usual to provide means for feeding water through the hollow steel to the cutting face of the bit and to take precautions against air passing into the shank of the steel. One arrangement for these purposes consists in the provision of a water tube fixed axially in the machine having its forward end extending into the shank of the hollow steel and its rear end communicating with the water line. According to this arrangement care must be taken to see that the hole in the shank is sufficiently large in order to permit the water tube to enter the shank freely, otherwise damage to the tube will result.

The construction briefly outlined in the last preceding paragraph and other known constructions are defective in that—

(a) Air is always present in the chuck cavity under more or less pressure and finds its way through the steel to the cutting face.

(b) Water pressure at the cutting face of bit is considerably less than water line pressure owing to leakage into the chuck.

The object of the present invention is to provide a rock drill of the type referred to or like percussive tool which shall be free of the defects above set out.

In accordance with my invention I provide a rock drill of the hammer type or like percussive tool having a water tube so arranged and combined that it is free or "floating" in the sense that it is not positively joined or rigidly fixed or secured so as to prevent longitudinal movement.

The forward end of the "floating" tube passes over or within the bore of the shank of the steel or the bore of the anvil block as the case may be and under all operative conditions is maintained so closely associated with the bore of the shank (or anvil block) by reason of pressure imparted at the rear end thereof, as to make and always maintain an airtight joint thereby preventing the escape of water from the tube into the chuck cavity and preventing also the entry of air from the chuck cavity into the shank.

In order that my invention may be readily understood and carried into practice ref-

erence is hereby made to the accompanying sheet of illustrative drawings, showing a 55 sectional view of an embodiment of my invention and from which it will be seen that in accordance with the example illustrated I provide a free or floating water tube A axially in the machine and passing 60 through the rifle bar (not shown) through a piston, only the front extension A' of which is shown, and into the shank B of the steel C. The forward end of the water tube is tapered at D and engages a shoulder E in the shank formed by a counterbore or otherwise, and the rear end is furnished with a spring F thus imparting pressure which causes the forward end of the tube to be maintained in close engagement 65 with the shank of the steel.

The spring F takes the form of a compression spring and is seated within a cylinder G in the handle H, the front end of the spring engaging a washer I loose in 75 the cylinder G and the rear end engaging a plug J. The loose washer I permits water to pass to the water tube from any suitable or usual water connection connected to the cylinder G forwardly of the washer. 80

The plug J may be so formed as to admit of the adjustment of the compression of the spring.

The washer I passes over the rear end of the tube A and is maintained in position 85 by an enlarged surface K being a ball formed near the rear end of the tube.

The forward end of the cylinder G carries a stuffing box and gland L.

Water delivered to a passage O in the 90 handle H through a suitable conduit (not shown) passes into a chamber P in the cylinder G, from whence it flows around the outer edge of the washer I and through the bore Q of the tube A into the drill steel C. 95

What I claim is:

In a rock drill of the hammer type, the combination of a casing and a hollow drill steel extending into the front end of the casing, a handle for the casing having a 100 cylinder therein, a water tube extending longitudinally through the handle cylinder and casing and into the shank of the drill steel to form an air tight connection therewith, an enlarged surface on the tube in 105 said handle cylinder, said water tube be-

ing free to move longitudinally and follow both the forward and the backward movements of the drill steel, and a compression spring at the rearward end of the water tube in said handle cylinder exerting pressure against said enlarged tube surface normally tending to force the water tube forwardly and maintain close contact between the

water tube and the drill steel, whereby air is prevented from passing down the drill ¹⁰ steel.

Signed at Johannesburg in the Transvaal Province of the Union of South Africa this 2nd day of September A. D. 1925.

WILLIAM JAMES BARNETT.
